UNITED STATES PATENT OFFICE

170,781

TOY FIGURE OR SIMILAR ARTICLE

Velma G. Weaver, Oklahoma City, Okla.

Application April 24, 1953, Serial No. 24,649

Term of patent 14 years

(Cl. D34—2)

To all whom it may concern:

Be it known that I, Velma G. Weaver, a citizen of the United States, residing at Oklahoma City, State of Oklahoma, have invented a new, original, and ornamental Design for a Toy Figure or Similar Article, of which the following is a specification, reference being had to accompanying drawing, forming a part hereof.

I claim:

The ornamental design for a toy figure or similar article, as shown.

VELMA G. WEAVER.
